UNITED STATES PATENT OFFICE.

GEORGE W. MOWRY, OF GENEVA, ASSIGNOR OF ONE-HALF TO FRANCIS M. SMITH, OF NEW YORK, N. Y.

BLACKING-BRUSH.

SPECIFICATION forming part of Letters Patent No. 328,599, dated October 20, 1885.

Application filed January 20, 1885. Serial No. 153,372. (No model.)

To all whom it may concern:

Be it known that I, GEORGE W. MOWRY, a citizen of the United States, residing at Geneva, in the county of Ontario and State of New 5 York, have invented certain new and useful Improvements in Blacking and other Brushes, of which the following is a specification, reference being had to the accompanying drawings.

10 This invention has relation to improvements in blacking-brushes for boots and shoes; and it consists in the construction and novel arrangement of devices, as will be hereinafter explained.

15 The annexed drawings, to which reference is made, fully illustrate my invention, in which Figure 1 represents a side view, part sectional, of my device. Fig. 2 is a plan view, partly in section, which is taken on line *x x*, 20 Fig. 1. Fig. 3 is a detail view of portions of the dip and arms *b*, showing the locking thumb-piece *l*; and Fig. 4 is a perspective view of the portion *C*, which supports the dip.

25 Referring by letter to the accompanying drawings, *A* designates the brush, which is usually provided with a recess, *a*, on its upper face and at the front end thereof, and *B* is the handle by which said brush is used.

30 *C* indicates a dip-supporter and blacking-holder, which is constructed usually of one piece of material of circular form, and is provided with upwardly-curved spring-arms *b* and lugs *c*, by which it is secured to the brush-body. A space, *d*, is provided in front of this supporter 35 for the introduction of the box containing the blacking, and a space or opening, *e*, is also provided in rear in order to permit the revolution of the dip *F*. In the upper end of one of the arms aforesaid is a perforation, *f*, or 40 bearing for the journal on one side of the dip, while the opposite arm thereto is provided with a longitudinal slot-bearing, *g*, which receives the opposite journal on the dip. This latter journal-bearing is of peculiar construction, 45 having a pointed shank, *i*, which enters the body of the dip, the same being rectangular in cross-section, to prevent the same from turning, unless it carries therewith the dip, and it is provided with side lugs, *j*, and a 50 rounded neck portion or bearing, *k*, between

said lugs and the thumb-piece *l*. The side walls of the supporter are provided with vertical slots *m*, through which pass and slide therein the hook ends *w* of a fulcrum-lever, *D*, which raises and lowers the blacking-box 55 *E* within the supporter, said lever being connected or pivoted thereto by the hook ends thereof, as shown in the drawings. This fulcrum-lever is usually made of a single piece of wire and fulcrumed at *p* to the top of the 60 handle of the brush, having the thumb portion *r*, whereby the same is operated. A spring is placed between said lever and the brush-handle to keep said lever in position when not pressed upon. 65

It will be observed from the above description, and by reference to the annexed drawings, that the box *E*, containing the blacking, is raised up to the brush by the fulcrum-lever. The operator pressing on the thumb-portion 70 thereof causes this upward movement to said box when the same is held in close contact with the dip, the operator then forcing the dip laterally by the thumb-piece *l*, thus bringing the round portion *k* or journal within the 75 slot, thus enabling him to give the dip a forward and backward movement, and at the same time applying blacking from the box to the bristles of the dip. After this operation the dip is turned with its bristles upward, 80 when the lugs on the journal-bearing will spring into the longitudinal slot in the side arm. The latter, being yielding, serves as a spring, whereby the journal aforesaid is automatically locked in position. This last-described position of the dip presents the same 85 ready for use in applying the blacking to the shoe.

When the dip is not in use, the same may be turned, bringing the bristles within the support, which also serves as a protector therefor; and it will be noticed that only a half-revolution of said dip is necessary in putting it in the different positions. 90

By my device blacking is saved from waste, 95 the blacking of shoes is quickly and easily accomplished, and the dip is free from surplusage, and at the same time it is durable, and cheap to manufacture.

Having described my invention, what I 100

claim, and desire to secure by Letters Patent, is—

1. The combination, with the brush, of the support C, having the arms adapted to receive between them the dip and journaled thereto, the side slots, m, in its lower end, the box E, and fulerum-lever D, as and for the purpose set forth.

2. The combination, with the brush, of the support, cut away as shown, leaving the spaces in front and in rear, and provided with the vertical slots in its side walls, the curved spring-arms having the journal-bearings in their upper ends to receive the journals of the reversible dip, whereby the same is supported and locked in position, and the box pivoted to the fulerum-lever, the whole operating as set forth.

3. The combination, with the support, con-

structed as described, the brush, and reversible dip, of the lever and box, the latter pivoted to the former by the hook ends of the lever, and constructed of a single wire fulcrumed to the handle, and having a spring engaging the lever, whereby said lever is held in its normal position, as and for the purpose set forth.

4. The combination, with the brush, the lever, box, and support, constructed as described, of the dip provided with the journals, substantially as shown, whereby the dip may be reversed and locked in position, as set forth.

In testimony whereof I affix my signature in presence of two witnesses:

GEORGE W. MOWRY.

Witnesses:

S. SOUTHWORTH,
CHAS. H. RUSH.
